UNITED STATES PATENT OFFICE.

HARRY C. KROMER, OF BALTIMORE, MARYLAND.

DESIGN FOR A LAUNDRY-WAGON.

SPECIFICATION forming part of Design No. 20,122, dated August 26, 1890.

Application filed December 12, 1889. Serial No. 333,540. Term of patent 14 years.

To all whom it may concern:

Be it known that I, HARRY C. KROMER, a citizen of the United States, and a resident of Baltimore, Maryland, have invented a new and original Design for a Laundry-Delivery Wagon, of which the following is a specification.

My design for a laundry-delivery wagon is shown in the accompanying drawing, which represents an isometrical perspective view of the wagon.

The dash represents a section of a wash-tub A, containing an upright wash-board B.

The driver's seat is a representation of a wash-boiler D, having the front portion cut away and having the lid D, mounted on standards a a, so as to constitute a hood for the seat.

The body F of the wagon consists of a many-sided drum, with semi-cylindrical guard b in the lower portion.

The rear seat consists of a representation of a smoothing-iron G, with rim h extending across the same at the rear and part way along each side. This latter feature, however, is immaterial and may be omitted without departing from the essential characteristics of the design. 25

I claim—

The design for a laundry-delivery wagon, substantially as described, and as shown in the accompanying drawing. 30

In testimony whereof I have signed my name to this specification in the presence of two subscribing witnesses.

HARRY C. KROMER.

Witnesses:

IDA B. KROMER,
G. E. REARDON.
